UNITED STATES PATENT OFFICE.

RUDOLPH ROHLEEN, OF SEATTLE, WASHINGTON.

ATTACHMENT FOR MITER-BOXES.

1,286,417.

Specification of Letters Patent.

Patented Dec. 3, 1918.

Application filed July 29, 1918. Serial No. 247,135.

To all whom it may concern:

Be it known that I, RUDOLPH ROHLEEN, a citizen of the United States, and resident of Seattle, in the county of King and State 5 of Washington, have invented certain new and useful Improvements in Attachments for Miter-Boxes, of which the following is a clear and exact specification.

This invention relates to improvements in 10 attachments for miter boxes and the object of this improvement is to provide an attachment that may readily be secured to the vertical side of a miter box and quickly and easily adjusted into various angles of divergence from said vertical side to support 15 a piece of timber in an inclined position with respect to both the vertical side and the horizontal bottom of the miter box so that the piece of timber may be miter cut 20 on an angle with respect to all of its side surfaces.

When a piece of timber of rectangular shape is laid flat on the horizontal bottom side of a miter box and cut at an angle by 25 turning the miter saw at other than right angles to the vertical side of the box, the plane of the cut surface of the timber will be at right angles to the plane of the top and bottom surfaces of the timber, and at other 30 than right angles to the two side surfaces of the piece of timber. If the piece of timber is turned so that none of its side surfaces are parallel with the plane of the bottom of the miter box and then cut with the 35 saw at other than right angles to the back of the box, the plane of the miter cut end will not be at right angles to any of the side surfaces of the piece of timber.

The attachment disclosed in this applica- 40 tion is adapted to support a piece of timber in an inclined position so that its side surfaces are not parallel with the bottom and side of the miter box respectively.

The invention consists in the novel con- 45 struction of an attachment of the class de- scribed and the adaptation and combination of the attachment with a miter box as will be more clearly hereinafter described and claimed.

50 In the drawings, Figure 1 is a plan view of a miter box showing two attachments constructed in accordance with this invention placed thereon. Fig. 2 is an enlarged view in cross section substantially on broken line

2—2 of Fig. 1, portions of the box and the 55 miter saw being broken away, and Fig. 3 is a view in perspective of one of the miter box attachments constructed in accordance with this invention.

Referring to the drawings, throughout 60 which like reference numerals indicate like parts, numeral 5 designates a miter box of well known form of construction that is provided with a horizontal table or bottom 6 and with a vertical side 7 arranged at right 65 angles to the bottom 6 and adapted to cooperate therewith to support a piece of timber indicated by a dotted line 8 that is to be sawed.

The side of the box 7 as herein shown is 70 formed of corrugated metal but it is obvious that these attachments will work equally well on a box having a straight, non-corrugated vertical side.

The box 5 is provided with a transverse 75 bar 10 pivoted as at 11 and adapted to support two upright saw guides 12 and 13 wherein is mounted a reciprocable saw 14 that may be turned at other than right angles to the side 7 of the box, all of the above 80 parts being of well known standard construction.

This invention contemplates the provision of a pair of attachments that are adapted to be secured to the side 7 of the miter box 85 on each side of the saw and adjusted into various angular positions with respect to the side 7 to form a support and guide for the side of the piece of timber 8 that is to be sawed.

The attachments each comprise a flat plate 15 that is provided near each end with hook shaped members 16 that are adapted to hook over the top edge of the side 7 as more clearly shown in Fig. 2, and to be secured 95 thereto by set screws 17.

The rear side of the plate 15 is preferably recessed for the reception of the downwardly projecting ends 18 of the hook members 16 which extend entirely across the 100 plates 15 and are secured thereto by screws 20.

The plates 15 are supported by the hook members 16 in such a position that they will just clear the bottom 6 of the miter 105 box, and such plates 15 are provided near their bottom edges with holes 21 wherein are disposed screws 22 that are threaded

through the depending portions 18 of the hook members and are adapted to be screwed against the vertical side 7 of the miter box to support the lower edge of the plate 15 at a desired distance from the side 7.

One end of each of the plates 15 is preferably beveled as at 23 so that it will clear the saw 14 when the saw is turned at an angle to the side 7.

10 The beveled ends 23 of the plates 15 are also preferably cut at an angle that is inclined away from the saw 14 from top to bottom of the plates so that when the bottom edges of the plates 15 are moved outwardly by turning the screws 22 the lower portions of the beveled ends 23 will not interfere with the saw 14. The plates may be made in pairs for the right and left side of the miter box respectively, or such plates 15 may be provided with bevels 23 on both ends in an obvious manner so they will be interchangeable with respect to the two sides of the box.

25 The front surface of the plates 15 are preferably roughened or serrated so that a piece of timber will have less tendency to slide thereover and the bottom table 6 of the miter box is usually roughened in a similar manner.

30 This device is especially useful in cabinet making and pattern shops, and in the interior finishing of boats where pieces of timbers are often placed together in various inclined positions.

35 When the screws 22 are not in engagement with the side 7 but are withdrawn to permit the depending end 18 of the hook members 16 to hang in a vertical position then the plates 15 will be parallel with the 40 side wall 7 and the miter box may be used in the ordinary manner without removing these attachments therefrom.

45 In operation, if it is desired to cut the piece of rectangular timber 8 on an angle with respect to two of its sides it may be placed on the bottom of the box 6 with one side in contact with the vertical plates 15 and cut in a plane at right angles to the top and bottom surfaces of the timber 8 and at other than right angles to the side surfaces of such timber.

50 If, however, it is desired to cut the timber 8 at an angle other than a right angle to all of its sides the screws 22 may be screwed inwardly against the plate 7 far enough to give the plates 15 the desired angle and the piece of timber 8 may be held securely against the plates 15 and sawed.

55 It is obvious that changes in the form of construction and arrangement of the parts

of the attachments herein described may be resorted to within the scope of the claims.

What I claim and desire to protect by Letters Patent is—

1. The combination with a miter box having a horizontal bottom and side walls at right angles thereto, of plates connected at their top edges with the top edges of said side walls and means for moving the bottom edges of said plates away from said side walls. 65

2. The combination with a miter box having a horizontal bottom and a side wall at right angles thereto, of a plate having hooks on the top edge thereof that hook over the top edge of said side wall, and screws in the bottom edges of said plates that are adapted to engage the lower portion of said side wall to support said plate at an angle with respect to said side wall. 75

3. The combination with a miter box having a horizontal bottom and a side wall at right angles thereto, of a plate having hooks on the top edge thereof that hook over the top edge of said side wall, and screws in the bottom edges of said plates that are adapted to engage the lower portion of said side wall to support said plate at an angle with respect to said side wall, said plate being cut at an angle and beveled on one end to clear the saw of said miter box. 85

4. An attachment of the class described comprising a plate having a beveled inner end that is cut on an incline from top to bottom, a strap secured to the rear side of said plate adjacent each end thereof, rearwardly directed hooks formed on the upper ends of said straps, and screws adapted to screw through said straps, said plates being provided with recesses wherein said screws 95 are disposed. 100

5. An attachment for miter boxes comprising a plate having an inner end that is cut on an angle from top to bottom thereof and is beveled on said inner end to clear a saw said plate having grooves formed in the rear side thereof, straps disposed in said grooves and secured to said plates, outwardly directed hook portions formed on the top ends of said straps, set screws provided in said hook portions and screws threaded through the lower ends of said straps the said plate being provided with recesses wherein said screws are operatively disposed so that they will not project outwardly from the plane of the front surface of said plate. 110

Signed at Seattle, Washington, this 6th day of July, 1918.

RUDOLPH ROHLEEN.
